PROCESS FOR THE ISOMERIZATION OF ALKYL BENZENES

Ronald S. Barlett, Thornton, Glenn O. Michaels, Park Forest, and Owen H. Thomas, Dolton, Ill., assignors, by mesne assignments, to Sinclair Research, Inc., New York, N.Y., a corporation of Delaware

No Drawing. Filed Apr. 12, 1960, Ser. No. 21,598
9 Claims. (Cl. 260—668)

This invention relates to a process for the isomerization of alkyl aromatics.

It is known from the literature that isomerizations involving changes in the carbon content of alkyl groups attached to the aromatic ring, as for instance isomerization of ethyl and larger alkyl group aromatics to their corresponding methyl derivatives, usually proceeds slower than positional group isomerization. Since commercial feeds of interest contain a spectrum of alkyl aromatic derivatives, any product recycle process must minimize these reaction rate differences in order to avoid a build-up of non-reactive aromatics in the recycle stream.

One procedure for minimizing any differential in reaction rates between these two types of alkyl aromatic isomerization involves the use of a two-stage process. In the first-stage alkyl aromatics are hydrogenated to their corresponding naphthalene derivatives and then isomerized. This is followed by a second-stage operation involving naphthalene dehydrogenation and final isomerization. The advantage claimed by this two-step approach is that the alkyl aromatic isomerization of certain refractory derivatives proceeds at a faster rate through the naphthalene homologues. In most processes, unless the reaction is carried out in two stages, formation of, for example, polymethyl aromatics from their corresponding ethyl and isopropyl aromatic isomers leads to dealkylation side reactions.

We have now discovered a process where both types of isomerization, i.e. positional isomerization and isomerizations involving changes in the carbon content of alkyl groups attached to the aromatic ring, can be carried out in a single stage to produce appreciable yields of the desired product. In the single-stage process of the present invention a favorable naphthalene-aromatic "steady state" can be attained and the naphthalenes can, if desired, be recycled continuously in the mother liquor after removal of the desired isomerate by crystallization. Generally, about 0.1 to 20%, preferably about 1 to 7 percent, by weight of naphthalenes is produced or is present in the reaction product.

According to the present invention a benzene aromatic hydrocarbon in the C_8 to C_{10} range having one or more alkyl groups of 1 to 3 carbon atoms in length, preferably C_1 to C_2 , attached to the aromatic ring is contacted under isomerization conditions and in the presence of hydrogen with a catalyst consisting essentially of alumina and catalytic amounts of boria and a platinum group metal.

The isomerization reaction conditions of the present invention include a temperature sufficient to maintain the alkyl aromatic feed in the vapor phase under the pressure employed. Generally this temperature will be from about 550 to 950° F., preferably about 750 to 825° F., while the pressure will be superatmospheric, for instance, ranging from about 50 to 2000 p.s.i.g., preferably about 150 to 600 p.s.i.g. The catalyst can be used as a fixed, moving or fluidized bed or in any other convenient type of handling system. The fixed bed system seems most advantageous at this time and the weight hourly spaced velocity will in most cases be from about 0.25 to 50, preferably about 1 to 10. Free molecular hydrogen must be present in our reaction system and the hydrogen to

2

alkyl aromatic molar ratio will usually be from about 1 to 20:1 or more, preferably about 6 to 12:1.

Our hydrocarbon conversion catalyst includes catalytically effective amounts of a noble or platinum group metal and boria supported on an alumina base. The catalyst generally contains about 0.05 to 2 weight percent, preferably 0.1 to 1 weight percent, of one or more of the platinum metals of group VIII, that is platinum, palladium, rhodium, ruthenium, osmium or iridium, with the metals having face centered cubes being preferred. The small amount of noble metal may be present in the metallic form or as a sulfide, oxide or other combined form. The metal may interact with other constituents of the catalyst, but if during use the noble metal be present in metallic form then it is preferred that it be so finely divided that it is not detectable by X-ray diffraction means, i.e. that it exists as crystals of less than about 50 Angstrom units size. Of the noble metals platinum, palladium and rhodium are used most advantageously.

The boria components is surface dispersible on the support, and therefore it is preferably added in direct proportion to the area of the support. For instance, the amount of boria will usually be about 0.5 to 20 weight percent, and preferably about 5 to 15 weight percent, of the catalyst. These amounts are particularly effective on aluminas having surface areas of about 350 to 600 square meters per gram (BET) before use.

The noble metal and boria constituents of the catalyst are deposited on an absorptive alumina base of the activated or calcined type. The base is usually the major component of the catalyst, generally constituting at least about 75 weight percent on the basis of the catalyst, preferably at least about 80 to 90%. The catalyst base is an activated or gamma-alumina such as those derived by calcination of amorphous hydrous alumina, alumina monohydrate, alumina trihydrate or their mixtures. The catalyst base precursor most advantageously is a mixture predominating, for instance about 65 to 95 weight percent, in one or more of the alumina trihydrates, bayerite I, bayerite II (randomite or nordstrandite) or gibbsite, and about 5 to 35 weight percent of alumina monohydrate (boehmite), amorphous hydrous alumina or their mixture. The alumina base can contain small amounts of other solid oxides such as silica, magnesia, natural or activated clays (such as kaolinite, montmorillonite, halloysite, etc.), titania, zirconia, etc., or their mixtures. Although the components of the catalyst can vary as stated, a preferred catalyst contains platinum and boria deposited on activated alumina at least about 200 square meters per gram surface area before use.

As previously stated the preferred catalyst base material is an activated or gamma-alumina made by calcining a precursor predominating in alumina trihydrate. An alumina of this type is disclosed in U.S. Patent No. 2,838,444. The alumina base is derived from a precursor alumina hydrate composition containing about 65 to 95 weight percent of one or more of the alumina trihydrate forms gibbsite, bayerite I and bayerite II (randomite or nordstrandite) as defined by X-ray diffraction analysis. The substantial balance of the hydrate is amorphous hydrous or monohydrate alumina. Trihydrates are present as well defined crystallites; that is, they are crystalline in form when examined by X-ray diffraction means. The crystallite size of the precursor alumina trihydrate is relatively large and usually is in the 100 to 1000 Angstrom unit range. The calcined alumina has a large portion of its pore volume in the pore size range of about 100 to 1000 Angstrom units generally having about 0.1 to about 0.5 and preferably about 0.15 to about 0.3 cc./g. of pore volume in this range. As described in the patent the calcined catalyst base can be characterized

by large surface area ranging from about 350 to about 550 or more square meters/gram when in the virgin state as determined, for example, by the BET adsorption technique. A low area catalyst base prepared by treating the predominantly trihydrate base precursor is described in U.S. Patent No. 2,838,445. This base when in the virgin state has substantially no pores of radius less than about 10 Angstrom units and the surface area of the catalyst base is less than about 350 square meters/gram and most advantageously is in the range of about 150 to 300 square meters/gram.

The platinum group metal component of the catalyst can be added to the alumina base by known procedures. For instance, the platinum metal component can be deposited on a calcined or activated alumina, but it is preferred to add the platinum metal component to the alumina hydrate precursor. Thus platinum can be added through reaction of a halogen platinum acid, for instance, fluoro-, chloro-, bromo- or iodo-platinic acid, and hydrogen sulfide in an aqueous slurry of the alumina hydrate. The hydrogen sulfide can be employed as a gas or an aqueous solution. Alternatively, the platinum component can be provided by mixing an aqueous platinum sulfide sol with the alumina hydrate. This sol can be made by reaction in an aqueous medium of a halogen platinic acid with hydrogen sulfide. The alumina hydrate containing the platinum metal can be dried and calcined usually at a temperature from about 750 to 1200° F. or more to provide the activated or gamma-alumina modifications. The boria can be added to the catalyst in any stage of its preparation. It may be incorporated in the support, for instance, by precipitation, coprecipitation, impregnation, and mulling either before or after the addition of the group VIII metal. It can also be applied by impregnation from solution (water, organic or inorganic solvents) or from a gas phase. However, it is frequently added to the catalyst after it has been formed by tableting or extrusion and calcined. After the boria is added in this procedure the catalyst can be recalcined. Preferably, the boria is added by pouring a hot solution of boric acid over the platinum alumina catalyst, stirring thoroughly, and then drying and calcining.

The catalyst of the present invention can be easily

10 regenerated employing conventional procedures, for instance, by subjecting it to an oxygen-containing gas at temperatures sufficient to burn off carbon deposited on the catalyst during the conversion of petroleum hydrocarbon feedstock. This oxygen-containing gas, e.g. an oxygen-nitrogen mixture, can contain about 0.01 weight percent to 5 weight percent oxygen but preferably contains about 0.5 to 1.5 weight percent oxygen and is introduced at a flow rate such that the maximum temperature at the site of combustion is below about 1000° F.

15 The alkyl aromatic feed material employed in our process is a material that contains as a major fraction a C_8 to C_{10} benzene aromatic hydrocarbon having attached to its aromatic ring one or more alkyl groups in the C_1 to C_3 carbon length range, preferably 1 or 2 carbon atoms. The preferred alkyl aromatic feeds are those containing C_8 , C_9 and C_{10} derivatives as the major fraction. C_{10} derivatives can be obtained from durene crystallized mother liquors which are composed of durene, isodurene, 20 small amounts of prehnitene with the remainder being primarily ethylxylenes.

25 The following specific examples will serve to illustrate our invention but are not to be considered limiting.

EXAMPLE I

30 300 grams of a calcined platinum-alumina catalyst of the type described in U.S. Patent No. 2,838,444 were weighed into a 6" crystallizing dish. The catalyst analyzed 0.6% platinum and at the time of platinum addition and 35 before calcination the alumina comprised about 70% trihydrate (42% bayerite, 18% randomite, 11% gibbsite) with the remaining being substantially of the amorphous or monohydrate forms. After calcination at a maximum temperature of about 925° F. the catalyst composition 40 had an area (BET method) within the range from about 350 to 550 square meters per gram. 59 grams of H_3BO_3 were dissolved in 279 ml. of deionized water by heating to boiling. The hot boric acid solution was poured over the platinum-alumina catalyst and stirred thoroughly with a rubber spatula. The catalyst was placed in a forced air drying oven, set at 284° F. for 4 hours. The catalyst was stirred occasionally while drying. The oven-dried catalyst was transferred to a sagger and placed in a

^a Data from I.E. Chem., April 1955, p. 770.

^b Percent of equilibrium yield for a given isomer is defined as 100 times the mole fraction of a given isomer in normalized Cs isomerate either divided into or by the equilibrium isomer mole fraction depending on whether feed composition is short or in excess of equilibrium.

muffle furnace preheated to 1000° F. The catalyst was held at 1000° F. for 2 hours and cooled in a desiccator. Analysis 9.95% B_2O_3 .

EXAMPLE II

A 1" universal stainless steel reactor is charged with 88 g. (100 cc.) of a platinum-alumina-boria catalyst prepared essentially as above. Hydrogen flow is maintained at a rate of 0.5 to 1.0 cubic foot per hour for 3 hours to insure platinum reduction. At this time alkyl aromatic feeds A, B and C were passed over the catalyst from a pump and the reaction was conducted under the conditions shown in Table I. At the end of a three-hour reaction period the runs were terminated and the products analyzed by mass spectrograph and infra-red. The results are shown in Table I. In addition, published data on processes employing a platinum- SiO_2 - Al_2O_3 catalyst in single and two stages are shown for comparison. The reaction conditions and feeds employed in these runs and the results found are also shown in Table I.

EXAMPLE III

Ethyl benzene was isomerized in accordance with the general procedure of Example I employing the catalyst of that example. For comparative purposes published data showing ethyl benzene isomerized in a single and two-stage processes using platinum- SiO_2 - Al_2O_3 catalyst are given. The reaction conditions feed compositions and results are shown in Table II.

^b Defined in Table I

A comparison of the data in Tables I and II shows that both positional group isomerization and those involving side chain contraction and expansion can be carried out in one stage with platinum-boria alumina at conversion levels comparable to or better than those obtained with platinum on silica-alumina in two stages. In Table I, for example, the yields of meta, ortho and para xylenes (percent of equilibrium) in the first run (A), which employed the single-stage process of the present invention, were substantially that produced by the two-stage process, yet the process of the present invention yielded 80% (of equilibrium) of ethylbenzene compared to the 39% yielded by the two-stage process.

In Table II, for example, the ethylbenzene conversion of the process of the present invention was 64 compared to 62 for the two-stage process while the xylene yields were in general quite similar. The advantages of the present process over the single-stage method represented by the published data are apparent.

EXAMPLE IV

In accordance with the general procedure of Example I a tetra-methylbenzene feedstock was isomerized using the catalyst of Example I to produce the desirable chemical intermediate durene. The results are shown in Tables IIIa and IIIb.

^b Defined as in Table I.

Examination shows that the absence of platinum on the boria impregnated alumina results in a composition that is significantly inferior both for positional group isomerizations as well as the type involved in xyleneethyl benzene interconversion. In addition, the data of Table IV indicates the advantageous effect of boria on an 0.6% Pt— Al_2O_3 catalyst when used for alkyl aromatic isomerization. Even when operating at a 100° F. higher temperature at a lower space velocity, xylene isomerization with platinum-alumina gives a lower conversion than that found for its boria-containing analogue.

We claim:

1. A process for the isomerization of C_8 to C_{10} alkyl-benzene hydrocarbons having at least one alkyl group containing 1 to 3 carbon atoms which comprises contacting a feed consisting essentially of alkyl aromatic hydrocarbons containing at least a major fraction of said C_8 to C_{10} alkyl-benzene hydrocarbons under vaporphase isomerization conditions at a temperature of about 550 to 950° F. and in the presence of free hydrogen with a catalyst consisting essentially of alumina and catalytic amounts of boria and a platinum group metal the isomerizate reaction product having about 0.1 to 20% naphthene.

2. The process of claim 1 wherein the alkyl group contains 1 to 2 carbon atoms.

3. The process of claim 2 wherein the catalyst consists

essentially of alumina, about 0.1 to 1 weight percent of platinum group metal and about 5 to 15 weight percent boria.

4. The process of claim 3 wherein the platinum group metal is platinum.

5. The process of claim 4 wherein the alumina is derived by calcination of hydrous alumina containing about 65 to 95 percent trihydrate and has a surface area of about 350 to 550 square meters/gram before use.

10 6. The process of claim 1 wherein the temperature is about 750 to 825° F.

7. The process of claim 4 wherein the temperature is about 750 to 825° F.

15 8. The process of claim 7 wherein the isomerizate product has about 1 to 7% naphthene.

9. The process of claim 1 wherein the isomerizate product has about 1 to 7% naphthene.
